UNITED STATES PATENT OFFICE.

JAMES MARIAN VAUGHN, OF WATER VALLEY, KENTUCKY.

CAR-COUPLING.

SPECIFICATION forming part of Letters Patent No. 425,275, dated April 8, 1890.

Application filed September 14, 1889. Serial No. 323,908. (No model.)

To all whom it may concern:

Be it known that I, JAMES MARIAN VAUGHN, a citizen of the United States, and a resident of Water Valley, in the county of Graves and 5 State of Kentucky, have invented certain new and useful Improvements in Car-Couplings; and I do hereby declare that the following is a full, clear, and exact description of the invention, which will enable others skilled in the 10 art to which it appertains to make and use the same, reference being had to the accompanying drawings, which form a part of this specification, and in which—

Figure 1 is a perspective view of a draw-head fitted with my coupling, the greater part 15 of the draw-bars being broken away. Fig. 2 is a longitudinal vertical sectional view of a pair of the same, and Fig. 3 is a perspective detail view of one of the couplings detached 20 from the draw-head.

This invention relates to car-couplings, having reference particularly to that class of 25 couplings employing a link and spring-actuated hook or tongue.

My object is to provide a compact coupling 30 of this class composed of few parts, said parts being of simple construction, strong, and so arranged as to be easily adjusted.

My device is illustrated in the accompanying 35 drawings, in which like letters of reference denote corresponding parts in all the figures.

The letters A designate the draw-heads, which are preferably rectangular in cross- 40 section. Near the top of said draw-head is placed a horizontal shaft B, one end of which is provided with a handle C. The other end of the shaft is furnished with a washer D, and is perforated for the insertion of a key for retaining 45 said shaft in the draw-head, and also for the insertion of one end of the spring hereinafter described. Near the center of the shaft and within the draw-head is placed the tongue E, adjustable on said shaft and fixed as adjusted by means of the set-screw e. The spring F has one end inserted in the perforation of the shaft B, before referred to. The spring is then bent, as shown in the drawings, and has its other end retained by a staple or guide f. The handle C has a notch c, and a button or latch G is fastened to the top

of the draw-head in such a position that it can be made to catch in said notch when the handle is pressed forward. The draw-head is also provided with the link-guide H, having 55 a handle h upon each side. The link used in connection with my coupling is of the ordinary construction, and therefore needs no particular description.

The operation and advantages of my invention are, briefly stated, as follows: The tongue E is raised by pressing the handle C forward, and thus a link may be inserted in either of the draw-heads, or the tongue is pressed back by simply shoving the link 60 against it. The spring F brings the handle back and the tongue down, so as to retain the link whenever the handle is released. When the link has thus been placed in one of the draw-heads, the cars are ready for coupling, 65 and by coming together with the usual force the other end of the link strikes the tongue in the corresponding coupling of the other car and raises the tongue sufficiently to slide in. In some cases it may be necessary to guide 70 or raise the link slightly, in order to insure its entrance into the draw-head. This is done by means of the link-guide H, which is operated by means of either of its handles h.

It is often desirable in switching cars to 75 have the couplings so arranged that they may come together without fastening. For this purpose I employ the latch G, hereinbefore described, and by pressing the handle C forward and detaining it with the latch the tongue E is raised, so that the link may pass 80 in and out without being detained.

It will be seen that the spring by which the tongue is brought down is simply a steel rod bent into the proper shape, and that it is 85 where it can be replaced or repaired easily in case it fails to work. By making the tongue adjustable on the shaft it can be changed to vary the tension of the spring and to overcome the effect of wear.

Having thus described my invention, I 90 claim and desire to secure by Letters Patent of the United States—

1. The combination, in a car-coupling of the class described, of the draw-heads, the coupling-link shaft having a notched handle, tongue adjustably fixed to said shaft, and a

latch for holding said handle forward, substantially as shown.

2. The combination, in a car-coupling of the class described, of the draw-heads having 5 perforations, as shown, the shaft inserted through said perforations and having a notched handle at one end and a perforation at the other end, a latch adapted to engage 10 said notch in the handle, the tongue, coupling-pin, an exterior spring having one end inserted in the perforation of the shaft, and

the staple or strap adapted to retain the other end of said spring, all constructed and combined to co-operate substantially as and for the purpose set forth.

In testimony that I claim the foregoing as my own I have hereunto affixed my signature in presence of two witnesses.

JAMES MARIAN VAUGHN.
